WILLIAM J. BROWN, OF NEWARK, NEW JERSEY, ASSIGNOR TO SPLITDORF ELECTRICAL COMPANY, OF NEWARK, NEW JERSEY.

ATTACHING MEANS FOR IGNITION BREAKER-BOXES.

1,251,472.

Specification of Letters Patent.

Patented Jan. 1, 1918.

Application filed May 14, 1917. Serial No. 168,582.

To all whom it may concern:

Be it known that I, WILLIAM J. BROWN, a citizen of the United States, residing at Newark, in the county of Essex and State 5 of New Jersey, have invented certain new and useful Improvements in Attaching Means for Ignition Breaker-Boxes, of which the following is a specification.

My invention relates to means for attaching breaker boxes to ignition devices, such 10 as magnetos, and, as illustrated in the accompanying drawing, is particularly adapted for use in connection with an inductor type of magneto in which the induction coil is carried on the magnetic field directing 15 structure which is revoluble about the axis of the rotating inductor; the field structure being revoluble for the purpose of keeping the same relative position of break between the poles of the inductor and the pole pieces 20 of the induction coil while adjusting the time of break of the primary circuit. In structures of this nature, the parts that are revoluble for the purpose of adjusting the 25 time of ignition have considerable inertia and the timing lever used for moving the revoluble parts must be securely fastened to the said parts, it being common practice for a number of manufacturing reasons to 30 make the breaker box carrying the timing lever a separate part from the rest of the members constituting the revoluble structure.

It is the object of my invention to provide 35 means for fastening the breaker box carrying the timing lever to that member of the revoluble structure to which the member is attached, such that the fastening will be simple, and therefore cheap to manufacture, 40 as well as one that will not give way under the strains to which it is subjected.

While obtaining a secure means for fastening the breaker box to one of the revoluble members, it is another object of 45 my invention to provide a ready means of adjusting the position of the breaker box on the said member before the securing means is brought into action.

These and other objects of my invention 50 will be understood on referring to the drawing, in which Figure 1 is a part elevation

and sectional view of a magneto known as the Dixie type.

Fig. 2 is a sectional view on the line 2—2 through the breaker box, bearing holder 55 and fastening means.

Fig. 3 is a perspective view of the bearing holder of Fig. 1 with the breaker box removed but with the clamping ring in position within the bearing holder.

Referring now particularly to the details illustrated in the various views, in which like numbers refer to corresponding parts, 60 1 is the base of a magneto having a rear end plate 2 and front end plate 3 between 65 which are mounted magnets 4, one of which is shown removed. The end plate 2 carries a bearing holder 5 and the end plate 3 carries a bearing holder 6 having bearings 7 (only one of which is shown) mounted 70 therein. Bearing holder 5 has a flange 8 fastened to a field pole structure 9 by screws 10. Bearing holder 6 has a flange 11 fastened to the field pole structure 9 by screws 12 which pass through screw holes 75 13. The flange 11 also has holes 14 for dowel pins to assist in alining the bearing holder 6 on the field pole structure 9. The field pole structure 9 carries the usual magnetic laminations 15 between the legs of which is carried an induction coil 16, one end of the primary of said coil being carried out to the breaker box, through slot 39 in flange 11 and groove 38 in sleeve 28, by a suitable 80 insulated conductor 17. Bearing holder 6 is slotted at 18 for the gear 19 that meshes with the distributor gear 20 which is used to drive the distributor for distributing the sparks from the secondary of the coil 16 to the various plug wires connected to the 85 posts 21 (only 2 of which are shown). The parts of the field structure, the coil, distributor, etc., will not be further described 90 as they form no part of my invention and have only been mentioned for the general descriptive purposes of the magneto to which my invention is applied.

Coming now particularly to the features of my invention it will be seen that the bearing holders 5 and 6, which are fastened 100 by means of flanges 8 and 11 to the field pole structure 9 carrying the laminations

15 and induction coil 16, constitute a rotatable structure having considerable inertia and since changes in magnetic flux through the laminations 15 and core 22 of coil 16
5 are produced by a rotor carried on and driven by the shaft 23 the rotatable structure mentioned, if the same position of break at the field poles be maintained, must be adjustable around the axis of rotation of
10 the rotor while adjusting the time of spark produced by the cam 24 carried on the end of the rotor shaft 23, the same being held thereto by screw 25, as this cam acts on the circuit breaker (one member only of which
15 is shown at 26) and the breaker box 27, on which the breaker elements including part 26 are mounted, must be securely fastened to the end of the bearing holder 6. The breaker mechanism forming no part of this
20 invention is not further described and for sake of clearness is not shown in detail, however, a suitable type of breaker is illustrated in Patent #1,190,785, issued July 11, 1916 to C. T. Mason. To accomplish the purpose
25 I set within the outward projecting sleeve 28 of the bearing holder 6 a relatively heavy ring 29, preferably slotted at 30 so it will have a certain amount of resiliency. The rim of the breaker box 27 is adapted to pass
30 over the end of sleeve 28 and be in a plane adjacent the ring 29. Screws 31 and 32 are adapted to pass through holes in the rim of the breaker box 27 and through slots 33 and 34 in the end of sleeve 28 and into tapped
35 holes 35 and 36 in the ends of the ring 29, which has a portion removed so that it does not form a complete annular ring. It will be seen that when the screws 31 and 32 are turned in the proper direction the ring 29
40 will be expanded against the inner walls of the sleeve 28, gripping the same very tightly. The slots 33 and 34 are made of some length, as shown, so that the breaker box 27 and the ring 29 may be rotated on
45 the sleeve 28 to get the breaker box lever 37 in any desired position with reference to the revoluble structure before the screws 31 and 32 are operated to expand the ring 29 for the purpose explained.
50 After the breaker box has been securely clamped to the sleeve 28 of the bearing holder 6 it will be seen that any movement of the lever arm 37 will cause the entire field pole structure to be moved for the purpose
55 of keeping the same relative position of break of the rotor from the field poles, at the same time the position of the breaker arm 26 on the breaker box 27 is moved with reference to the cam 24.
60 In the past the breaker box has been held to the sleeve 28 of bearing holder 6 or its equivalent by various means, such as screws, but these become loosened or break off and allow the breaker box to slip thereby chang-

ing the timing of the magneto. The construction as above described overcomes these difficulties and while I have shown one method of adjustment and fastening I do not wish to be limited to the exact details shown. 65

Having thus described my invention what I claim is:—

1. In an ignition device, a source of magnetic flux, an ignition coil having primary and secondary windings and relatively stationary means for directing the flux through said coil windings, a timing member for adjusting the time of action of the primary of said coil and the passage of flux through the windings, said timing means having an 80 element fastened to the flux directing means, a divided ring mounted within the extremity of said element, said timing member being mounted on the exterior of said element adjacent said divided ring and means mounted 85 in the timing member and coöperating with said ring for drawing said ring securely against the inner periphery of said element for the purpose described.

2. In an ignition device, a revoluble structure carrying flux directing members and an induction coil having primary and secondary windings in operative relation thereto, said revoluble structure also having a bearing holder having a sleeve extending laterally therefrom, a divided ring positioned within and at the extremity of said sleeve, a breaker box carrying means for controlling the primary circuit of the coil, said box being mounted on the outer extremity of 100 said sleeve adjacent said ring and means on the breaker box passing through the said sleeve for drawing the ring securely against said sleeve for the purpose described. 90

3. In an ignition device, a revoluble structure carrying flux directing members and an induction coil having primary and secondary windings in operative relation thereto, said revoluble structure also having a bearing holder having a sleeve extending laterally therefrom, an expansible member positioned within and at the extremity of said sleeve, a breaker box for controlling the action of said coil windings, said box being carried on the sleeve adjacent the expansible 115 member and means fastened to the breaker box for expanding the expansible member against the sleeve whereby the breaker box is securely fastened thereto. 110

4. In an ignition device, a revoluble structure carrying flux directing members and an induction coil having primary and secondary windings in operative relation thereto, said revoluble structure also having a bearing holder having a sleeve extending laterally therefrom, an expansible member positioned within and at the extremity of said sleeve, a breaker box for controlling the 120 125

action of said coil windings, said box being carried on the sleeve adjacent the expandible member and means for first adjusting the breaker box in position on the sleeve and 5 means for securely fastening the box to the sleeve by expanding the expandible member as described.

5. In an ignition device, a revoluble structure carrying flux directing members and 10 an induction coil having primary and secondary windings in operative relation thereto, said revoluble structure also having a bearing holder having a sleeve extending laterally therefrom, a relatively heavy member 15 having means for rendering it resilient positioned within the end of the sleeve, a breaker box for controlling the ignition circuits mounted on the end of the sleeve adjacent said member, and means carried on 20 the breaker box and coöperating with the said member to clamp the breaker box, mem-

ber and sleeve securely together for the purpose described.

6. In combination, a breaker box for controlling an ignition circuit, a support for 25 said box, an expandible member within said support and means carried by said box for expanding said expandible member whereby it clamps the box and support securely together.

7. In combination, a breaker box for controlling an ignition circuit, a support for 30 said box, an expandible member within said support and screw adjusting means carried by said box for adjusting its position and 35 said support, said screws also serving to spread the ends of said expandible member to grip the support for the purpose described.

In witness whereof I affix my signature. 40

WILLIAM J. BROWN.
